UNITED STATES PATENT OFFICE.

ARTHUR W. EATON, OF BOSTON, MASSACHUSETTS, ASSIGNOR TO UNITED SHOE MACHINERY COMPANY, OF PATERSON, NEW JERSEY, A CORPORATION OF NEW JERSEY.

HAND-TACKER.

No. 856,399.

Specification of Letters Patent.

Patented June 11, 1907.

Application filed June 18, 1900. Serial No. 20,693.

To all whom it may concern:

Be it known that I, ARTHUR W. EATON, a citizen of the United States, residing at Boston, in the county of Suffolk and State of 5 Massachusetts, have invented certain new and useful Improvements in Hand-Tackers; and I do hereby declare the following to be a full, clear, and exact description of the invention, such as will enable others skilled in 10 the art to which it appertains to make and use the same.

The present invention relates to hand tacking devices or tools used for driving tacks into the upper and insole of boots and shoes 15 during the operation of lasting.

The object of the present invention is to produce a hand tacking tool of simple form and arrangement in which the tacks contained in a hopper are arranged to be shaken 20 up and agitated and properly guided into the race-way without the necessity of employing movable lifters, gates and similar devices, the ordinary motions imparted to the tool during its movements over the shoe being lasted, 25 and the jar imparted thereto by the operation of driving the tacks, being sufficient to cause a supply of tacks to fill the race-way.

To the above end the present invention consists of the devices and combinations of 30 devices which will hereinafter be described and claimed.

The present invention is shown in the accompanying drawings in which—

Figure 1 shows a vertical section taken on 35 the line $x-x$ Fig. 2, Fig. 2 shows a front elevation of the tacker, Fig. 3 shows a rear elevation of the tacker with the raceway broken off, Fig. 4 shows a sectional view through the hopper taken on the line $y-y$ Fig. 1, and 40 Fig. 5 shows a sectional view of the hopper taken on line $z-z$ Fig. 4.

Similar reference numerals will be employed throughout the specification and drawings to designate corresponding parts.

In the drawing 1 indicates the tacker, 2 the feeding chute and 3 the hopper. The tacker comprises a frame 4 to be grasped by the hand, said frame being of substantially cylindrical form and carrying at its lower end a 45 head 5 and a nose 6, a tack driving passage 7 being formed in said head and nose.

The frame 4 is provided with a longitudinal bearing 8 in which is fitted to slide a tack

driver plunger 9 to which is secured a tack driver 10 arranged to drive the tack out of 55 the driving passage 7 into the work. The plunger 9 extends upward beyond the top of the frame 4 and at its upper end is provided with a head 11 which is adapted to receive blows of a mallet or other device used to depress said plunger to drive the tacks. The plunger is normally held raised by a coiled spring 12 which surrounds its upper end and which bears at its upper end against the under side of the head 11, and at its lower end is 60 seated in a chamber 13 formed in the upper end of the frame 4.

The frame 4 is provided with diametrically disposed longitudinal slots 14 and 15 into which project the opposite ends of a stud 16 70 carried by the plunger 9 which forms a stop to limit the upward throw of the plunger. As the frames of tackers are usually formed of comparatively soft metal such as cast brass, in order to prevent the undue wear 75 thereof, caused by the forcible impact of the stop stud 16 with the upper ends of the slots 14 and 15 under the force of the return stroke of the spring 12, I have provided the hard metal wear plates 17 and 18 which are secured to the frame 4 by any suitable means, such as screws 19, to receive the blows of the stop block 16. The slot 14 permits access to 80 the interior of the driver 4 without dismantling the device. Said slot is closed during 85 the operation of the machine by a removable sliding plate 20 which fits in guides 21 formed adjacent to the edges of the slot 14 and said sliding plate is held in said guides by means of a screw 22.

The raceway 2 may be of any usual or preferred form and is formed of two plates 24 fastened together along the lower edges by means of bolts or rivets 25 and spacing plates 26 so as to form a channel down which the 95 tacks slide to the driver passage. The raceway 2 is secured by means of screws 27 in an inclined position, to an arm 28 projected rearwardly from the frame 4, and its lower end enters an opening 29 formed in the head 100 5 so as to deliver tacks into the driver passage 7. The lower end of the raceway 2 is notched as shown at 30 and such notches cooperate with a separating gate 31 to separate the lowermost tack in the raceway and deliver it into the driver passage 7.

The separator gate 31 slides in a recess across the lower end of the raceway and is reciprocated at each reciprocation of the driver plunger 9, by means of a lever 32 which is pivotally mounted upon a stud 33 at its upper end and supports at its lower end said gate, said lever having upon its inner face a cam path 34 which is engaged by a cam roll 35 mounted upon the stud 16.

10 The cam path 34 is so shaped that when the driver 9 is at the limit of its downward travel the separator gate 31 is at the limit of its outward throw, and then as the plunger rises, the gate moves inwardly and separates one 15 tack from the row of tacks in the race and then stands still until the driver rises above the tack, when the gate completes its inward movement and forces the tack into position under the driver. It will be noted that the 20 movements of the gate are positive and certain, thus positive control of the tack at all times is secured.

The head 5 carries spring pressed pins 36 which project into the driver passage 7 and 25 support the tacks therein beneath the tack driver in position to be driven upon the descent of said driver.

As shown in the drawing, the upper end of the raceway is formed at an angle to the 30 inclined portion thereof and extends substantially at a right angle to the tacker 1. Supported upon the upper end of the raceway is a hopper 3 which is formed preferably of some light sheet metal such as sheet iron. 35 The hopper shown in the drawing is substantially oblong or rectangular in shape and the raceway leads into the same by a slot formed in the front of the said hopper and extends back along the longitudinal center of said 40 hopper, said hopper being secured permanently to the raceway in any suitable manner, as by the block 39 which is secured by the bolts or rivets 38 to the end of the raceway 2, and the screws 40 passing through the 45 end of the hopper 3 and entering said block 39.

As will be noted from Figs. 1 and 5 of the drawing, the upper edge of that part of the raceway which extends into the hopper is formed in two planes, the edge of the forward 50 portion being substantially horizontal and the rear portion being inclined, forming an angle at 42, and the bottom of the tack containing chamber of the hopper is formed upon two inclines which meet at the angle 55 42. The forward part of the bottom of the tack containing chamber is formed by the plates 43 secured in position upon opposite sides of the raceway, and the rear part of the bottom of the tack containing chamber is 60 formed by a plate 44 which is supported by the raceway 2 and is fastened in position by the downwardly extending lugs 45 through which the screws 40* which pass through the sides of the hopper, pass. This plate 44 is 65 provided with a slot 46 opening into the

raceway and with converging guide ribs 47 to guide the tacks into the raceway.

It will be noted that the forward part of the bottom of the tack containing chamber forms comparatively deep pockets upon opposite sides of the raceway which receive the mass of tacks, and that when the tool is shaken or agitated some of the tacks will be thrown upon the plate 44 and because of the inclination thereof and the presence of the 75 guide ribs 47 a few of the tacks will be retained on said plate to be guided into the raceway.

The hopper is provided with a cover 48, which is hinged thereto at one end by a hinge 80 49 and provided at its opposite end with a spring latch 50 which engages a pin 51.

The raceway 2 is provided with the usual guard plate 52 supported above the same to prevent the tacks from accidentally falling 85 out.

The operation of the device having been sufficiently described in connection with the foregoing description, a further description thereof will be unnecessary.

Having described the construction and mode of operation of my invention, I claim as new and desire to protect by Letters Patent of the United States.

1. In a hand tacker, the combination with 95 the tack driver and raceway, of a hopper supported by said raceway, said hopper having at one end inclined pockets upon opposite sides of the raceway and at the opposite end a guide plate provided with converging 100 guide ribs, upon which plate the tacks are discharged from the inclined pockets, substantially as described.

2. In a hand tacker, the combination with 105 an inclined raceway, of a hopper supported thereby, said hopper having at one end thereof a slotted guide plate inclined in the opposite direction to the raceway and provided with converging guide ribs, substantially as described.

3. In a hand tacker, the combination with 110 an inclined raceway, of a hopper supported thereby, a slotted guide plate provided with guide ribs, the ribs converging for one portion of their length and extending substantially parallel for another portion of their length, substantially as described.

4. In a hand tacker, the combination with 115 the tack driver and raceway, of a separating gate acting to withdraw from in front of the raceway when the driver is depressed to permit the tacks to advance along said raceway until the leading tack contacts with the driver, and to return to its first position in two movements with a dwell between to permit the driver to rise above the tack, and means for actuating the gate, substantially as described.

5. In a hand tacker, the combination of a 120 driver, a hopper, and a raceway extending 125

into the hopper and terminating intermediate the ends thereof, the bottom of the hopper being divided near the end of the raceway into two portions inclining oppositely, so that when the driver is in its normal position the forward part of the said bottom is inclined toward the driver and the latter part away therefrom, and guiding means on

the latter part to guide the tacks into the raceway, substantially as described. ¹⁰

In testimony whereof I affix my signature, in presence of two witnesses.

ARTHUR W. EATON.
